UNITED STATES PATENT OFFICE

LEE DE FOREST, OF NEW YORK, N. Y., ASSIGNOR, BY MESNE ASSIGNMENTS, TO GENERAL TALKING PICTURES CORPORATION, A CORPORATION OF DELAWARE

SOUND REPRODUCER

Application filed September 11, 1926. Serial No. 134,781.

This invention relates broadly to improved sound reproducing combinations.

One of the objects of this invention is the provision of a suitable form of sound 5 reproducing device for use in conjunction with motion picture screens in auditoriums.

Another object of this invention is to produce a combination in which the loud speaker is so arranged with respect to the motion 10 picture screen that the sounds issuing therefrom will appear to emanate from the screen.

A still further object of this invention is to so combine the loud speaking device with the screen structure that they may be moved 15 conjointly out of their normal position when it is desired to utilize the stage for other purposes.

A still further object of this invention is to so arrange the aperture of the loud speaking device so that its major axis is horizontal. 20

A still further object of the invention is the disposition of a loud speaking device of relatively long dimensions, whose major axis 25 is parallel to the plane of the screen.

These and many other objects are successfully sought by my invention, as will appear from the following description.

This invention resides substantially in the 30 combination, construction, arrangement and relative location of parts, as will appear in the following disclosure.

Referring to the drawings—

Fig. 1 represents a front elevational view 35 of a motion picture screen supporting a loud speaking unit particularly devised therefor by me.

Fig. 2 represents a side elevational view of this construction, and

Fig. 3 represents a vertical cross-sectional view of the arrangement of Fig. 1, taken on the line 3—3 of Fig. 1, looking in the direction of the arrows.

Heretofore when talking motion pictures 45 have been presented in the theatre, it has

been customary to use for loud speakers either one horn located on the stage directly beneath the screen, or two,—one located on either side of the screen. The ordinary motion picture screen is of canvas or rubber 50 and much too thick to permit the loud speaker horn to be placed back of the screen and the sound waves to permeate through the screen itself. At the same time, it is highly desirable from the standpoint of illusion that the loud speaker horns be as near 55 as possible to the screen so that the observers in the audience hearing the sound emanating from some source and watching the figure on the screen will instinctively think 60 that the sound emanates from the lips of the speaker or from the musical instruments depicted on the screen.

Such horns as I have described are bulky; and frequently it is impractical from the 65 standpoint of stage requirements to have these horns so located below the screen or on either side thereof. A practical arrangement requires that the horn should be in fact an integral portion of the screen framework, 70 and itself always in place relative to this screen even when the screen, as is frequently the case, must be suddenly lifted from its position in view of the audience to an elevated position along the flies above the 75 stage, in order to clear the stage quickly for presentation of acts, etc., thereon. All of the above considerations render the ordinary form of loud speaker horn quite unsuited for use in the average motion picture 80 house where the screen must be frequently elevated and lowered, and where only small space is permissible between the screen and the upper flies, or between the screen and the back wall of the stage.

Moreover, I have found that for satisfactory realism in talking motion pictures a very large horn is highly desirable or essential. A horn for a low "cut-off" value, that is, one capable of faithfully reproducing 85

the lowest notes or tones of the lowest frequency which are heard in orchestra reproduction, is highly desirable. I have discovered a method of conforming to these 5 ordinarily conflicting conditions and have designed a type of horn which combines great length with large cubic volume and large cross-section of aperture, together with shallow depth, this permitting the horn to 10 be placed close to the back face of this screen, and yet permitting the large aperture to be exposed above the screen.

Referring to the drawings, a framework 1, of any suitable construction, is provided 15 for supporting the screen 2 in any of the desired and well known manners. Supported on the screen framework is a loud speaking horn 3, having its aperture disposed at the top of the screen framework and parallel 20 to the plane thereof. At the small end of the horn is provided any suitable sound reproducing unit 4, which, in the arrangement shown, is supplied by actuating electric currents through the cable 5.

25 It will be noted that the horn portion of the sound reproducing device is very long with respect to its cross-sectional dimensions, and is of constantly increasing cross-sectional area from the smaller end towards 30 the aperture end. The aperture of the horn is preferably made short in a vertical direction and long in a horizontal direction, and projects above the upper edge of the framework on which the screen is stretched. The 35 mouth of the horn lies in a horizontal plane parallel to that of the screen, but the axis of the main part of the horn itself runs vertically, close to the screen and directly behind same, as is clearly shown in the figures. By 40 such an arrangement I am enabled to secure a great length of horn—as much as twenty (20) feet for the larger theatres (where the greatest volume of sound output is required) combined with a depth of horn not necessarily exceeding twelve (12), or eighteen (18) 45 inches. At the same time the mouth of the horn being long horizontally, for example 48 inches, and short vertically, e. g. 18 inches, gives a very excellent diffusion of sound 50 throughout the amphitheatre, particularly in the vertical plane, so that the sound waves reach all parts of the auditorium, from the front orchestra seats almost directly below the screen to the upper regions of the balconies. For it is a well known law of acoustics 55 that sound diffraction results in a diffusion of the sound in planes at right-angles to the long axis of a rectangular opening of a horn rather than in planes parallel to said 60 long axis.

The construction of a horn such as I have described lends itself very easily to the theoretically correct shape for horns—i. e. following the logarithmic or exponential law.

65 This law is briefly expressed as follows:

$A_x = A_o e^{Bx}$. Wherein in A_o is the cross-sectional area of the horn at the small end. A_x is the cross-sectional area of the horn at any point along its major axis "X" and "B" is a constant determined by the overall length of the horn and the two terminal areas thereof. The "cut-off" frequency of such a horn is

$$f = \frac{BV}{4\pi}$$

75

Where V = velocity of sound, 1100 feet per second, and B is the parameter of the horn. This "cut-off" frequency for such a horn as above described, having an overall length 80 of eleven (11) feet measured along its center axis and an opening of $48'' \times 18''$, is of the order of 80; that is, such a horn will reproduce clearly sound frequencies as low as 85 80 per second. Such an exponential horn as I have described has no resonant frequency, and reproduces with practically equal volume all sound frequencies above its lower "cut-off" level.

Moreover an exponential horn can be made 90 with much smaller dimensions than any other shape of horn giving equal performance. It is for example much superior to the conical type of horn.

Although I can reverse the position of the horn relative to the screen as shown in Figure "1"—that is have its aperture appear at the bottom of the screen, rather than at its top—I have found that both the acoustical effects and the illusion are better when the horn's large aperture is located above the screen, as shown.

Instead of one horn located in the middle of the screen as shown in Figure "1", I 100 may use two or more placed behind the screen, their apertures projecting above the top of the screen. Or I may place these two horns horizontally, behind the screen, and have the apertures thereof appearing at the two lateral margins of the screen. But in 105 every case the horn or horns are preferably fastened bodily to the screen, and are made an integral part of the screen structure, so that they travel with the screen when the same is raised or lowered.

I, of course, intend it to be within the scope of my invention to utilize more than one loud speaking device, when desirable, and to dispose them upon the supporting framework in any effective manner; for instance, several of them may be disposed along the upper surface, if desired.

I am aware that many changes in the details of construction and relative arrangement of parts will readily occur to those skilled in the art, and I do not, therefore, desire to be limited to the particular construction disclosed for purposes of illustration, but rather to my invention as I define it in the appended claim.

130

What I seek to secure by United States Letters Patent is:

A unitary structure of the type described comprising a frame, a reflecting screen supported on said frame, and a horn supported on said frame, said horn having a long neck of reducing cross section toward one end and a bell at the other, the neck and plane of the bell being substantially parallel to the screen and the bell lying substantially in the plane of the screen.

In testimony whereof I have hereunto set my hand on this 31st day of August, A. D. 1926.
